UNITED STATES PATENT OFFICE.

ORRIN CADY, OF CINCINNATI, OHIO.

SPIITTOON.

No. 846,454.

Specification of Letters Patent.

Patented March 12, 1907.

Application filed March 7, 1906. Serial No. 304,637.

To all whom it may concern:

Be it known that I, ORRIN CADY, a citizen of the United States, and residing at Cincinnati, Hamilton county, State of Ohio, have 5 invented certain new and useful Improvements in Spittoons; and I do declare the following to be a clear, full, and exact description of the invention, attention being called to the accompanying drawing, with the reference characters marked thereon, which form also a part of this specification.

This invention relates to a spittoon provided with certain features of improvements, as more fully described hereinafter and 15 pointed out in the claim, and as illustrated in the accompanying drawing, in which—

Figure 1 shows a top view of my improved spittoon. Fig. 2 shows a side view of the same. Fig. 3 is an under side view of it. 20 Fig. 4 is a cross-section, and Fig. 5 an end view. Fig. 6 in a sectional view shows a certain feature formed in a modified way.

One of the features of this improved spittoon is a formation which prevents it from 25 being readily tipped over or upset—as, for instance, in case a person's foot comes in contact with it. This effect is partly obtained by the size, as compared with the body B of the spittoon, of its bottom A and 30 by the shape of this latter, which is flat and has two parallel sides *a a* and is elongated between these sides and extended beyond them, terminating in pointed ends, as best shown in Fig. 3, whereby upsetting in a longitudinal direction is prevented. (Observe 35 also dotted lines in Fig. 2.)

Upsetting transversely is prevented by 40 elongated handles *b b*, which, substantially cylindrical or in form of a roll, extend laterally from opposite sides of the body and one each above the sides *a a*, with which they are parallel and partly coextensive. In 45 upsetting transversely the spittoon would naturally cant on one of these sides; but the tendency to turn over in this direction is quickly checked as soon as the particular

handle comes in contact with the floor. (See dotted lines in Fig. 5.) These handles serve also to manipulate the spittoon—as, for instance, when the same is to be emptied. To 50 facilitate such emptying, a snout or lip C is provided in the funnel-shaped rim D, which projects from the upper part of the body proper. This snout is so located as to be between the handles, thus rendering the act 55 of emptying the spittoon more convenient by concentrating the discharge. The shape of the body is also oblong to conform to the shape of the bottom and as shown. Rim D follows, of course, the shape of the body 60 and is provided with two snouts C C. They are diametrically opposite each other and in a line at right angles to the diametrical line in which the handles are located. This permits the spittoon to be conveniently tipped 65 for emptying in either direction after once grasped by the handles. This snout or lip may also be located below rim D, as shown in Fig. 6, which arrangement is particularly suitable where rim and body are round. 70

Having described my invention, I claim as new—

A spittoon which has a flat, elongated bottom with two parallel edges between which it is pointedly extended in opposite directions 75 beyond these edges, a body correspondingly elongated, an upwardly and outwardly inclined rim on said body and elongated handles parallel to each other and parallel to the edges of the bottom, provided on opposite 80 sides of the body below the rim of the same and projecting in a manner that if the spittoon is tilted on one of the parallel edges of its bottom, the particular handle on that side and above such edge will limit the tilting 85 movement, all as shown and described.

In testimony whereof I hereunto set my hand in presence of two witnesses.

ORRIN CADY.
